Nicholas Marchak, Mountainside, N.J., assignor, by mesne assignments, to American Can Company, New York, N.Y., a corporation of New Jersey

Filed Nov. 10, 1958, Ser. No. 53,317

Term of patent 14 years

(Cl. D58—17)

FIG. 1

FIG. 2

FIG. 3

FIGURE 1 is a side elevational view of a collapsible tube or similar article, showing my new design;

FIGURE 2 is a top plan view thereof; and

FIGURE 3 is an enlarged fragmentary detail view of the surface ornamentation applied to the top of the tube.

The dominant features of my design reside in the portions shown in full lines.

I claim:

The ornamental design for a collapsible tube or similar article, substantially as shown and described.
